SASH SEAT FOR DOUBLE HUNG WINDOWS

Thomas P. Koebel, Homewood, Ill., assignor to Zegers, Inc., a corporation of Illinois

Filed Mar. 12, 1958, Ser. No. 721,009

8 Claims. (Cl. 20—52)

My invention relates to a sash seat for double hung windows, and more particularly, to a sash seat for the modern double hung windows employing metal combination weatherstrip and sash guides along the window frame jambs.

Window structures of this type frequently employ sash guide tracks, mounted or formed in the guideways of the weatherstrip and sash guide members, which terminate well above the sill. The tracks are ordinarily of the same length for the inner and outer sash, but are sufficiently short so that when the sash are moved to their lowermost positions, the tracks protrude only a short distance into the complementary slide grooves that are formed in the sash side rails.

As the sill of the window ordinarily slopes downwardly outwardly of the window structure, the outer sash may be moved to a somewhat lower position than the inner sash, which effects a complete dislodgment of the sash from its tracks.

It has become a common practice to limit the possible downward movement of the outer sash by securing a sash seat in its guideways. Conventional sash seats of this type ordinarily are nailed into the jamb structure through the combination weatherstrip and sash guide members or are riveted to the latter.

Experience has shown that these conventional sash seats soon become detached in performing the very function for which they are provided. The shock they absorb when the sash is forced against them acts through a sizable lever arm to readily pry them away from the jamb or weatherstrip and guideway member to which they are attached. This necessarily results in unsightly holes and even tears being formed in the weatherstrip and guideway members, and materially detracts from their usefulness as weatherstripping. Unless the detached sash seats are re-secured in position, their useful service is prematurely ended.

A principal object of my invention is to provide a sash seat for double hung window structures that adequately resists any shocks applied thereto by the sash.

A further principal object of the invention is to provide a sash seat for double hung windows which eliminates the need for rigidly fixing the sash seat either to the jamb or to the combination weatherstrip and guideway unit.

Another object of the invention is to provide a sash seat for double hung windows that is economical of manufacture, that is easily and conveniently installed in operating position, and which is readily adapted for use on a wide variety of double hung window structures.

Other objects, uses and advantages will be obvious or become apparent from a consideration of the following detailed description and the application drawings.

In the drawings:

Figure 1 is a fragmental perspective view of a typical double hung window structure to which a preferred embodiment of my invention has been applied;

Figure 2 is a cross-sectional view through the window

2

structure approximately along the line 2—2 of Figure 1;

Figure 3 is a fragmental perspective view of the lower part of the window structure shown in Figure 1, on an enlarged scale and more particularly illustrating the application of the sash seat to the window structure;

Figure 4 is a top plan view of the sash seat shown in Figure 3;

Figure 5 is a side elevational view of the sash seat shown in Figure 3;

Figure 6 is a view similar to that of Figure 5 but showing the sash seat in its unlatched position; and

Figure 7 is an elevational view of the structure shown in Figure 3.

General description

Reference numeral 10 of Figures 1, 3 and 7, generally indicates a preferred form of my sash seat applied to a conventional double hung window structure 12 of the modern style. The window structure 12 includes upper and lower sashes 14 and 16 which ride on tracks 18 that are carried by combination weatherstrip and sash guide members 20. As is well known in the art, the sash side rails are conventionally formed with grooves that are complementary in shape to the shape of tracks 18. Springs 22 secured between the tops of the members 20 and the bottom rails of the sash bias the sash upwardly of the window structure.

The sash seat 10 is applied in the guideways 24 in which the outer sash 14 operates. As mentioned hereinbefore, the sill 26 of the window structure conventionally slopes downwardly outwardly of the window and the lengths of the outer track rails 18 are such that the outer sash would become dislodged from its tracks if the sash 14 were lowered into contact with the sill 26.

As best seen in Figure 3, the sash seat 10 comprises a strip of relatively stiff material 30, such as a suitable spring steel, that is formed into a generally right triangular configuration, including relatively straight legs 32 and 34 and hypotenuse portion 36, the hypotenuse 36 and the leg 34 being formed with interengaging locking means 38 whereby the ends of the strip are secured together.

The leg 32 of the strip 30 is placed behind the guideway 24 of the combination weatherstrip and guideway member and the leg 34 extends out into the guideway 24 through a perforation 40 formed in member 20.

The leg 34 is positioned sufficiently high above sill 26 to serve as an abutment against which the upper sash 12 engages when lowered to the broken line position of Figure 1 whereby the sash is maintained on its tracks 18. The hypotenuse portion 36 serves as a brace for the abutment forming portion 34 and the sash seat at its apex 42 is placed in engagement with sill 26 (see Figures 2 and 7).

Specific description

55 The specific window structure illustrated is shown and is specifically described only for purposes of facilitating an understanding of the invention, as will be understood by those skilled in the art. The typical window structure illustrated ordinarily includes side jambs 50, sill 26 and a head section 52 (see Figures 1 and 2). These members provide the familiar rectangular window frame in which is mounted the upper sash 14 and the lower sash 16. The combination weatherstrip and guideway members 20 are secured in any suitable manner to the respective jambs 50 and slidably mount the sashes 14 and 16 for the well known vertical movement.

60 The sashes ordinarily include side rails 56 that are formed with grooves 58 that are complementary in configuration to tracks 18. Top rails 60 and bottom rails 62 are united with the side rails 56 in any conventional manner to provide the usual association with window panes 64.

65 70 The sashes ordinarily include side rails 56 that are formed with grooves 58 that are complementary in configuration to tracks 18. Top rails 60 and bottom rails 62 are united with the side rails 56 in any conventional manner to provide the usual association with window panes 64.

The window structure illustrated also includes outer casing members 65, the ends of which project somewhat beyond the outer sides of the jambs 50 to provide outer stops for the upper sash 20, while the casing member 66 is provided across the top of the window frame at the outside thereof to form an outer stop for the upper sash 14 at the top of the window frame. On the inner side of the window, top stop strip 68 is provided together with side stop strips 70. At the bottom of the window, a stool member 72 is mounted above the window sill.

As best seen in Figures 1 and 3, the combination weatherstrip and guideway members 20 that are illustrated for purposes of description comprise a central channel 74 which provides a central parting stop, and laterally extending webs 76 and 78 that terminate in perpendicularly disposed flanges 80 that are adapted to cooperate with the sides 84 of channel 74 in providing the guideways of the members 20. The tracks 18 in the illustrated window structure each take the form of a metal strip 90 formed with a convexly rounded central portion 92 and flange portions 94 that are fixed to the respective webs 76 and 78 in any suitable manner so that the rounded portions 92 serve as sash tracks 18.

The strip 30 is preferably formed from spring steel shaped to approximately the configuration illustrated more particularly in Figures 4 through 6 and described in general above. Preferably, the hypotenuse portion 36 is crimped inwardly at its lower end as at 100 and the leg 32 is formed with a longitudinally extending corrugation or indentation 102. The crimped portion 100 of the hypotenuse portion 36 is preferably positioned so that the lower deflected portion 104 will abut against the lower end 106 of corrugation 102 when the ends of strip 30 are secured together in the manner indicated in Figure 5.

The outwardly projecting leg 34 adjacent its outer end is formed with perforation 110 for receiving a tongue 112 formed in the upper end of hypotenuse portion 36 to secure the ends of the strip together.

The seat 10 is applied to the outer guideway 24 of the combination weatherstrip and guideway member 20 by forming perforation 40 in the web 78 of a member 24 a sufficient height above its lower end to permit leg 34 to project through the perforation 40 when corner 120 of the seat is in alignment with the lowermost extremity 122 of the member 24 (see Figure 7). A relatively small triangular notch 124 is formed in members 20 where indicated to permit the seat 10 to fit in place. The seat 10 is then applied to the member 20, before it is secured against the window jamb, by unlatching hypotenuse portion 36 from leg 34 and inserting the lower edge 122 of the member 20 to the point within the seat that will permit the leg 34 to project through perforation 40. The tongue 112 of hypotenuse portion 36 is then moved into engagement with perforation 110 to lock the device in operating position with respect to the member 20. Member 20 may then be secured to the jamb in any conventional manner, with the result that the corner 120 of the seat 10 is placed in engagement with the sill 26 and leg 34 projects into the path of operation of sash 14. When the sash 14 is lowered to the broken line position of Figure 1, it engages the sash seat, which assures that the sash 14 will not become dislodged from its track.

Normally, a sash seat 10 would be employed on either side of the window though a single sash seat 10 will serve the purpose where this is desirable for reasons of economy.

It will be noted that the sash seat 10 is secured in place merely by being looped around the lower portion of web 78. The force that is applied to the seat when sash 14 is moved to its extreme open position is transferred directly to the sill through hypotenuse portion 36. Thus, it is not necessary to nail the seat to the

jamb or rivet it in any manner to the weatherstrip and guideway member 24.

The seat 10 actually forms a clip-like device in which the hypotenuse portion 36 and the leg 32 grip the web 78 when the ends of the strip 30 are secured together as described above. When member 20 is secured in place against the jamb, the leg 32 lies between the jamb and the web 78 which insures that the device is held in upright position.

10 The crimping of hypotenuse portion 36 at 100 provides a strengthening factor in the bracing portion of the seat since the columnar length that the shock load is applied to is materially reduced, and the shock load is applied in part to leg 32. This insures that the hypotenuse portion will not bend out of shape readily, and in any event, will not bend or buckle downwardly about apex 42.

15 I contemplate that the strip 30 will be plated to give it the same appearance as the members 24, which are ordinarily formed from aluminum.

20 It should therefore be appreciated that I have provided a simplified rugged sash seat which is designed to provide lasting service under continued use, even though it need not be nailed or riveted in place. The strip 30 is readily shaped to the configuration illustrated by simple manufacturing operations and installation of the seat requires only several simple cutting operations on the weatherstrip and guideway members that do not in any way adversely affect their appearance or functions.

25 The foregoing description and the drawings are given merely to explain and illustrate my invention and the invention is not to be limited thereto, except insofar as the appended claims are so limited, since those skilled in the art who have my disclosure before them will be able to make modifications and variations therein without departing from the scope of the invention.

30 I claim:

35 1. In a double hung vertically movable sash window structure including a frame having spaced side jambs, a sill, a combination weatherstrip and sash guide member secured to each jamb, defining guideways for the inner and outer sash, and inner and outer sash mounted between said members and running in said guideways, a sash seat for one of the sash comprising a relatively stiff member which in use is secured to one of the weatherstrip and guide members in the guideway for said one sash adjacent the lower end thereof, said relatively stiff member including a brace member which in use is placed in contact with the sill and interposed in the path of operation of the one sash, the length of said brace member being proportioned to stop the downward movement of the one sash at a predetermined distance above the sill.

40 2. In a double hung sash window structure including a window frame having spaced jambs, a sill, metal combination weatherstrip and sash guide members secured to each jamb, said members including guideways extending longitudinally thereof and having tracks secured in the upper portions of said guideways, and inner and outer sash mounted between said members and running on said tracks, said tracks terminating short of the lower ends of said members at least a distance that exceeds the height of the sash running thereon, a sash seat for one of the sash comprising a clip-like member secured to the lower end of one of the guideways in which said one sash runs, said clip-like member including a brace structure in contact with the sill and an abutment forming member secured to said brace structure and projecting into the path of movement of said one sash, said abutment forming member being positioned below the lower end of the track of said one sash a distance that is less than the height of said one sash, whereby said abutment forming member is positioned sufficiently high above the sill to stop downward movement of said one sash before it is disengaged from its track.

3. In a double hung sash window structure including a window frame having spaced jambs, a sill, metal combination weatherstrips and sash guide members secured to each jamb, said members including guideways extending longitudinally of said members and having tracks secured in the upper portions of said guideways, and inner and outer sash mounted between said members and running on said tracks, said tracks terminating short of the lower ends of said members at least a distance that exceeds the height of the sash running thereon, a sash seat for one of the sashes comprising a strip of relatively stiff material having its ends brought together and looped about the lower portion of the member in which said one sash runs, one portion of said strip contacting said sill and another portion passing through a perforation formed in the last mentioned member, the last mentioned portion defining an abutment structure projecting into the path of movement of said one sash, a further portion of said strip serving as a brace between said one portion thereof and said abutment structure, said abutment structure being positioned below the lower end of the track of said one sash a distance that is less than the height of said one sash, whereby said abutment forming member is positioned sufficiently high above the sill to stop downward movement of said one sash before it is disengaged from its track.

4. In a double hung sash window structure including a window frame having spaced jambs, a sill, metal combination weatherstrip and sash guide members secured to each jamb including guideways extending longitudinally of said members and tracks secured in the upper portions of said guideways, and inner and outer sash mounted between said members and running on said tracks, said tracks terminating short of the lower ends of said members at least a distance that exceeds the height of the sash running thereon, a sash seat for one of the sash comprising a strip of relatively stiff material having its ends secured together about a portion of one of said guideways that said one sash is guided by, said strip being formed into a generally right triangular cross-sectional configuration, one of the legs of said configuration extending behind the member defining said one guideway and the other of said legs projecting laterally of said one leg and through a perforation formed in the last mentioned member, and the hypotenuse of said configuration extending between said laterally projecting leg and said sill, said other leg being positioned below the lower end of the track of said one sash a distance that is less than the height of said one sash, whereby said abutment forming member is positioned sufficiently high above the sill to stop downward movement of said one sash before it is disengaged from its track.

5. The sash seat set forth in claim 4 wherein said hypotenuse is crimped inwardly at its lower end.

6. A sash seat comprising a strip of stiff resilient material bent into a right triangular configuration with the ends of said strip disposed in juxtaposition at one end of the hypotenuse and the adjacent end of one of the legs of said right triangular configuration, said strip ends

being formed with tongue and perforation means for securing said strip ends together, said hypotenuse being crimped inwardly at the other end thereof and toward the adjacent end of the other of the legs of said right triangular configuration, said other leg being indented toward said hypotenuse at least adjacent said crimped portion of said hypotenuse, said crimped portion of said hypotenuse and said indentation serving as clamping means when said ends of said strip are secured together, and said one leg serving as the sash engaging portion of the sash seat.

7. In a sash seat for a vertically movable sash window structure including a frame having spaced side jambs, a sill, a sash mounted between said jambs, and tracks interposed between said sash and said jambs defining means for guiding the vertical movement of the sash in the window structure, said sash seat comprising a relatively stiff member adapted to be secured below the tracks and at a corner of the window structure defined by one of the jambs and the sill, said member defining a projection which in use extends laterally of said one jamb and above said sill against which the sash is to engage when disposed at its lower limit of vertical movement within the window structure, said member also defining a brace portion extending from the projecting end of said projection and proportioned to engage the sill when in use, whereby said projection is braced against displacement when engaged by the sash.

8. In a sash seat for a vertically movable sash window structure including a frame having spaced side jambs, a sill, combination weatherstrip and sash guide members secured to each jamb including guideways extending longitudinally of said members and tracks secured in the upper portions of said guideways, and a sash mounted between said members and running on said tracks, said sash seat comprising a strip of relatively stiff material adapted to be disposed in a vertical plane and have its ends secured together about a portion of one of said members, said strip being formed into a generally right triangular cross-sectional configuration, one of the legs of said configuration in use extending behind said one member and the other of said legs projecting laterally of said one leg into the guideway defined by said one member through a perforation formed in said one member against which the sash rests at its lower limit of vertical movement within the window structure, and the hypotenuse of said configuration extending between said laterally projecting leg and said sill, whereby said other of said legs is braced against displacement when engaged by the sash.
